ELEVATOR

Clarence C. Crispen, Harrisburg, Pa., assignor to
 Inclinator Company of America, Harrisburg,
 Pa., a corporation of Pennsylvania

Application August 14, 1935, Serial No. 36,070

5 Claims. (Cl. 187—20)

This invention relates to a new and novel elevator or lift of very simple construction which particularly adapts the same for installation in places where the space available is limited, such as private homes, for example.

Another object of my invention is the provision of an elevator or lift so constructed as to reduce the cost of manufacture and installation to a minimum commensurate with good appearance 10 and safety.

A further object of my invention is the provision of a construction which enables an installation to be made in a finished building, the stair well of a private home, for example, without 15 spoiling the appearance of the room in which the elevator is installed and without marring or defacing the building.

In general my improved construction comprises a single vertically extending rail which receives a roller block or truck attached to the car platform, the rail supporting and guiding the car for movement vertically thereof, this same rail supporting the power unit or hoisting machine by which the car is driven. The bed plate of the 25 hoisting machine is so constructed as to fit over the top of the single rail, the hoisting machine being so disposed with reference to the rail that a minimum of anchorage of the bed plate to the rail is required. This permits of readily enclosing 30 the hoisting machine or power unit so that the whole will present a very neat appearance.

This arrangement also facilitates installation as compared with prior suggestions where the power plant or hoisting machine is placed in the 35 basement of the building.

It is to be distinctly understood that my improved machine may be installed in any type of building and its use, therefore, is not confined to private homes. I have mentioned its adaptability for installation in private homes merely to emphasize the simplicity and good construction 40 of my apparatus or machine where ease of installation is an important factor.

In the accompanying drawings wherein an 45 embodiment of my invention has been illustrated:

Fig. 1 is a fragmentary part sectional view of a portion of a house or building having an open stairway and showing my improved elevator installed in the stair well;

Fig. 2 is a sectional view taken on the line 2—2 of Fig. 4;

Fig. 3 is a section on the line 3—3 of Fig. 2;

Fig. 4 is a sectional elevational view showing 55 the hoisting machine, rail, etc. on an enlarged

scale with respect to the other figures of the drawings; and

Fig. 5 is a top plan view.

Referring to the drawings in detail, 1 designates the car which, as will be understood, may 5 be of any desired construction and comprises a car platform or floor 2. The car is adapted to be supported and guided for movement from one floor to another by a single vertically extending rail designated 3. The rail, as will be understood, 10 may be placed in vertical position in any desired location within a house or building and may be secured to a post of wood or metal 4 anchored, for example, to the floor of the building, the rail extending for a short distance above the top of 15 the car landing, as shown in Fig. 1, for instance. The rail 3 may be bolted, screwed or otherwise rigidly secured to this post.

At one side of the rail 1 secure a counterweight well or enclosure 5. 20

The rail 3 above referred to comprises a rear wall 6, side walls 7 and front flanges 8, the latter extending toward each other, and the whole construction providing a channel formation.

The car platform 2 extends into the rail between the flanges 8, as shown in Fig. 3, and is rigidly attached to a roller truck or block 9. This block or truck is equipped with a set of upper and lower rollers 10 journaled on the block and located between the rear wall 6 and the front 30 flanges 8 of the rail, being adapted to engage the opposing inner guiding surfaces of these members.

The block 9 also carries a second set of upper and lower rollers 11 adapted to engage the opposing inner guiding surfaces of the sides 7 of the rail 3. 35

By this construction it will be appreciated the car platform, which extends at right angles to the rail 3, will be guided and supported by the rail 40 for vertical movement relatively thereto.

As above pointed out one of the primary objects of the present invention is the provision of a simplified construction whereby the cost of installation is materially reduced as compared 45 with prior constructions. Consequently so far as the present structure is concerned instead of mounting the hoisting machine in the basement, for example, I propose to mount the same on the top or upper end of the rail 3. This hoisting 50 machine comprises a bed plate 13 provided on its underside with downwardly extending flanges 14 and 15 so designed as to fit over the top of the rail and to be bolted thereto, as shown in Fig. 4. On the bed plate 13 I mount the hoisting machine 55

which comprises motor 15, brake 16 and sheave 17 driven as for example through worm and gear drive, merely diagrammatically shown, from the motor 15 as will be understood.

5 The cables 18 which are attached to the block 9 and to the counterweight 12, which is suspended in the counterweight well 5, above referred to, pass over the traction sheave 17, as will be seen from Figs. 4 and 5, for instance.

10 The cable drum or traction sheave 17 is located directly above one side of the rail 3 so that the center of gravity of the combined weights of the car platform and counterweight 12 come directly over the rail in a manner requiring the minimum 15 of anchorage. As illustrated in the drawings the bed plate 13 is anchored to the rear wall of the rail and to one side wall by bolts 19.

15 As an alternative to this type of hoisting machine I may eliminate the counterweight entirely 20 and wind the cable on a grooved drum, as will be understood by those skilled in this art.

20 In Fig. 1 of the drawings I have shown the rail 3 secured to the post 4 at one side of the open stairway of a house or building in such 25 a position that the car platform may be raised and lowered between the lower floor 20 and upper floor landing 21 so that passengers may be carried in either direction from one floor to the other. It will be understood that when the car 30 platform 2 is down it rests upon the floor 20 and when raised the platform 2 is in a position flush with the floor 21. As mentioned above the car platform may be equipped with a suitable cage as usual and will of course be provided with a 35 door so that when the car is in raised position this door will be directly back of a door or gate provided in the stair railing at the upper floor 21.

35 Inasmuch as the platform 2 of the elevator car extends at right angles to the single rail 3 and 40 the platform is secured to the block or truck 9 the car and its load will be supported properly in the single rail due to the upper rollers 10 bearing against the front walls 8 of the rail and the lower rollers 10 bearing against the back wall 45 6 of the rail. The engagement of the rollers 11 with the side walls of the rail prevents the block or truck 9 and the car platform from tilting laterally during the raising and lowering of the car.

45 Suitable well known conventional electrical 50 switches may be employed at the two floors 20 and 21 and on the car itself for controlling the hoisting machine for raising and lowering the car.

50 The truck 9 is provided with a locking member 55 22 pivoted at 23. The end of this member is provided with teeth 24 adapted to be raised into engagement with one side wall of the rail 3 to force the rollers 11 at one side of the truck into engagement with the sides of the rail, there- 60 by to lock the block or truck 9 and the car against movement. This is a safety feature oper- 65 able, for example, in the event of breakage of the cables 18. The teeth 24 normally are held out of engagement with the rail due to the tension on the cables 18, but in the event of breakage of the cables then the spring 25 will pivot the member 22 about its pivot to bring the teeth 24 into engagement with the rail to hold the car against movement as above pointed out.

70 If desired a safety stop diaphragm structure may be employed beneath the car platform for automatically opening the elevator circuit should the car in its descent encounter an obstruction of any kind.

75 It will be seen from all of the foregoing that

the present invention provides an extremely sim- 5 ple and inexpensive elevator machine particu- 10 larly well suited for private house installation or where it is desired to convey passengers or other load from one floor to another.

It will be appreciated that by employing a single rail for supporting and guiding the car for vertical movement and by mounting the hoisting machine on the top of this rail the cost of in- 15 stallation is reduced to a minimum.

It will be appreciated also that this construc- 20 tion permits the hoisting machine to be covered over so as not to present an unsightly appearance, and that by mounting the machine so that the traction pulley overlies one side of the rail the hoisting machine may be held in place with prac- 25 tically no anchorage at all. I have found in actual practice that two bolts placed as I have shown on the drawings afford ample anchorage for the hoisting machine.

25 It is to be understood that changes may be made in the details of construction and arrangement of parts above described and shown in the accompanying drawings within the purview of my invention.

30 What I claim is:—

35 1. In an elevator, the combination of a car platform, a hoisting machine for raising and lowering the same, a bed plate for said hoisting machine, a single vertically extending rail for sup- 40 porting said car platform and the said hoisting machine, the car platform extending at right angles to the rail, the hoisting machine bed plate fitting over the top of the rail and being secured thereto.

45 2. In an elevator, the combination of a single vertically extending rail, a car platform extending from one side of the rail, means carried by the car platform and extending into the channel of said rail whereby the car platform is sup- 50 ported for movement relatively to the rail, a hoisting machine including a counterweight for raising and lowering the car platform, said hoist- 55 ing machine and the said counterweight being supported by said rail, the hoisting machine being mounted at the top of said rail, and a vertically extending counterweight well, lying beside said rail for receiving said counterweight.

60 3. In an elevator, the combination of a car platform, a hoisting machine for raising and low- 65 ering the car platform, a single vertically ex- 70 tends rail, a block secured to the car platform and extending into the channel of said rail whereby the car is supported for movement ver- 75 tically of the rail, said housing machine being mounted on the top of said single rail in line with said block.

75 4. In an elevator, the combination of a car platform, a hoisting machine for raising and low- 80 ering the same, a single vertically extending rail, a block secured to the car and extending into the channel of the rail and provided with rollers 85 engaging the rail surfaces thereby to support the car platform for movement vertically of said rail, said hoisting machine being mounted on the top of said single rail in line with said block.

90 5. In an elevator, the combination of a car platform, a hoisting machine for raising and low- 95 ering the car platform, a single vertically ex- 100 tends rail for supporting the said car platform, a bed plate for said hoisting machine, said bed plate being mounted at the top of said rail and provided with downwardly extending flanges tel- 105 escoping the sides and rear surfaces of said rail.

CERTIFICATE OF CORRECTION.

Patent No. 2,088,690.

August 3, 1937.

CLARENCE C. CRISPEN.

It is hereby certified that error appears in the printed specification of the above numbered patent requiring correction as follows: Page 2, second column, line 55, claim 3, for the word "housing" read hoisting; and that the said Letters Patent should be read with this correction therein that the same may conform to the record of the case in the Patent Office.

Signed and sealed this 21st day of September, A. D. 1937.

Henry Van Arsdale
